UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

RUNNING-BOARD SADDLE.

1,338,728.

Specification of Letters Patent.

Patented May 4, 1920.

Original application filed November 22, 1917, Serial No. 203,317. Patent No. 1,299,939, dated April 8, 1919.
Divided and this application filed August 30, 1918. Serial No. 251,999.

To all whom it may concern:

Be it known that I, DAVID W. HAWKSWORTH, a citizen of the United States of America, residing at Detroit, in the county 5 of Wayne and State of Michigan, have invented certain new and useful Improvements in Running-Board Saddles, of which the following is a specification, reference being had therein to the accompanying 10 drawings.

The invention relates to car roofs of that type in which the carlines are arranged above the roofing sheets and form the supports and weather-proofing caps therefor. 15 The present invention has particular reference to the construction of running-board saddle as hereinafter set forth. This application is a division of my prior application Serial No. 203,317, filed Nov. 22, 1917, for 20 car roof, which application resulted in Patent #1,299,939, issued April 8, 1919.

In the drawings:

Figure 1 is a cross-section through the car;

25 Fig. 2 is a cross-section through the center of the carline showing the manner of supporting the running board saddle;

Fig. 3 is an end elevation of the running-board saddle; and

30 Fig. 4 is a plan view thereof.

A are the carlines of inverted U cross-section having laterally-extending flanges at their lower ends, said carlines being arched transversely of the car and having down-turned end portions B overlapping the side of the car. C are the roofing sheets arranged beneath the carlines and which are provided at their sides edges with upturned flanges D return-bent and nested, and being 35 arranged within the channel of the carline. E are hanger bolts engaging slotted bearings F within the carlines and passing downward through apertures in the nested flanges D. G are bearing blocks mounted on 40 the hangers E and engaging the nested flanges, and H are nuts having threaded engagement with the lower ends of the hangers and supporting the blocks G. The construction as thus far described is similar to 45 roofs heretofore used and when applied to the car body, the downturned portions B of the carlines are bolted to the side plates of the car.

The running-board saddle may be at-

tached directly to the carline, as the latter is 55 above the roofing sheets. Inasmuch, however, as the carline is of arch form it is necessary either to form the saddle of a similar curvature or to provide other means for the proper bearing. This I have accomplished by forming a saddle of folded sheet metal comprising a top portion Q of greater width than the carline, with the return-bent flanges Q' and downturned flanges Q² which embrace the sides of the carline. The top 60 portion Q extends in the same plane from end to end of the saddle, but at the center of the ends there is a depressed portion R, as shown in Figs. 3 and 4, which is curved 65 to fit the upper surface of the carline and sufficiently depressed to support the ends 70 of the saddle when its center is resting upon the arch of the carline. The return-bent flanges are provided with a suitable number 75 of apertures S for the engagement of securing means for the running-boards and the saddle itself is secured to the carline by suitable means, such as the rivets T.

What I claim as my invention, is:

1. In a car roof, the combination with a 80 carline of arch form, of a running-board saddle secured to said carline comprising a flat top portion having downturned flanges for embracing the sides of the carline, and depressed bearings in the flat top portion at 85 the ends of said saddle for resting upon the carline.

2. In a car roof, the combination with a carline of arch form, of a running-board saddle secured to said carline comprising a 90 flat top portion of greater width than the carline, return-bent portions beneath said top portion having downturned flanges for embracing the sides of the carline, and depressed bearings in the flat top portion for 95 resting upon the carline.

3. In a car roof, the combination with a carline, of inverted channel cross-section, of a running-board saddle secured to said carline, comprising a flat top portion of greater 100 width than the carline, return-bent portions beneath said top portion having downturned flanges for embracing the sides of the carline and depressed bearings at the ends of the flat top portion for resting upon the 105 carline.

4. In a car roof, the combination with an arch-shaped carline, of a running-board sad-

dle formed of pressed sheet metal having a substantially flat top portion of greater width than the carline, return-bent portions beneath said top portion having downturned flanges for embracing the sides of the carline and secured thereto and depressed portions centrally at the ends of said flat top portion forming bearings upon the arch carline for supporting said flat portion in a plane above the center of the arch.

5. In a car roof, the combination with a carline of arch form, of a running board saddle secured to said carline, comprising a flat top portion of greater width than the carline, and return-bent portions beneath 15 said top portion having downturned flanges embracing and secured to the sides of the carline.

In testimony whereof I affix my signature.

DAVID W. HAWKSWORTH.
